UNITED STATES PATENT OFFICE.

DAVID D. GORDON AND WILLIAM LINDSAY, OF CHICAGO, ILLINOIS, ASSIGNEES TO ECONOMY FUSE AND MANUFACTURING COMPANY, OF CHICAGO, ILLINOIS, A CORPORATION OF NEW YORK.

ADJUSTABLE LIGHT-HOLDING MEANS.

Application filed June 8, 1925. Serial No. 35,506.

The present invention relates to adjustable light holding means.

An object of the present invention is to provide an electric light holding means which permits convenient adjustment in the positions of the electric light bulb or bulbs mounted therein.

A further object is to provide an efficient electric light cluster which is relatively simple and inexpensive to manufacture.

A further object is to provide an electric light holding means in which ready adjustability is had without the twisting of wires and without sacrifice of good electric conductivity between the source of electrical current and the electric lights carried by said holding means.

A further object is to provide an electric light cluster having switch means for independently controlling each socket in said cluster, which cluster involves a minimum of parts.

A further object is to provide an electric light cluster in which the various lights are readily and independently adjustable and which will remain in adjusted positions.

Further objects will appear as the description proceeds.

Referring to the drawings—

Figure 1 is a view in side elevation of an electric light cluster embodying the principles of the present invention;

Figure 2 is a view in elevation taken at right angles to the view shown in Figure 1;

Figure 3 is a view of one of the detachable parts of the construction shown in Figures 1 and 2;

Figure 4 is a view of a detachable part which is complementary to the part shown in Figure 3; and

Figure 5 is a view of a detail of construction.

Though the invention has a broad application and is applicable to holders for single lights as well as clusters, it will be illustrated and described in connection with a cluster suitable for use in a floor lamp. Due to the fact that various sizes and shapes of lamp shades are in common use, it is desirable to provide a lamp cluster which permits angular adjustment of the electric light bulbs relative to the standard of said floor lamp. With certain varieties of shade said electric light bulbs should be moved into rather

close proximity with said standard, whereas with other types of shade said electric light bulbs should be adjusted to a position to have as great a spread as possible relative to said standard.

In the drawings the numeral 1 indicates a tube forming part of a standard, which standard may be part of a floor lamp. Said tube houses the electric wires 2 and 3, which constitute the electric supply wires of said lamp. The upper extremity of the tube 1 is screw-threaded for the reception of the nut 4. The nut 4 has a part of its exterior of non-circular conformation, a hexagonal conformation being illustrated in the drawings.

Mounted in position to enclose the nut 4 is the housing 5, which housing comprises the two complementary sections 6 and 7. Said sections may be identical in conformation and are preferably composed of molded insulating material. Said two sections 6 and 7 have cooperating flat surfaces adapted to engage one another, and each of said sections is provided with recesses, to be referred to more in detail, for receiving the operating parts of the cluster.

Each of the sections 6 and 7 is provided with a recess 8 for the reception of switch mechanism, which switch mechanism is indicated as a whole by the numeral 10. The lamp cluster illustrated is adapted to support two electric light bulbs or other translating devices, and in order to independently control said two bulbs or other translating devices two independently operable switch mechanisms 10 are provided. The details of said switch mechanisms 10 are not part of the present invention. Preferably, however, they are of the type which are biased selectively to circuit-closing and circuit-opening positions. Each section 6 and 7 is provided with a chain guide 11, each of which accommodates a chain 12. Said chains 12—12 extend to regions in which they may be conveniently operated. Preferably, alternate pulls on either of said chains will bias the corresponding switch mechanism to open-circuiting or closed-circuiting position.

Each of the switch mechanisms 10—10 has a contact spring 13 extending therefrom. When the two sections 6 and 7 are placed together, said contact springs 13—13 will engage one another. One of said contact springs is permanently connected to the wire

3, so that one side of each of the switching mechanisms 10—10 is always connected in circuit. The other side of each of the switching mechanisms 10—10 is provided with the 5 conducting strip 14, which conducting strips 14—14 have portions 15—15 each adapted to receive and have electrical connection with one of the pins 16—16, each of which pins 16—16 is socketed at its two ends in the sections 6 and 7. As will be explained hereinafter, the two pins 16—16 are adapted to perform the double function of forming abutments for the center contact on an electric light plug and to provide electrical connection with said center contact.

Each of the sections 6 and 7 is also provided with a pair of recesses 17—17, which recesses have circumferential walls 18—18 lying in arcs having their axes coinciding with the longitudinal center lines of the pins 16—16. The two recesses 17—17 in each part 6 and 7 are divided by the partition 19, which partition is provided with the recess 20 shaped to conform to the nut 4. When 25 the two sections 6 and 7 are mounted together, the partitions 19—19 hold the nut 4 against either rotary or longitudinal movement. Said partitions 19—19 of the two sections 6 and 7 are grooved, as indicated by 30 the numeral 21, to permit the passage of the electric wires 2 and 3.

The recesses 17—17 have communication with the outside of the housing 4 through the elongated slots 22—22. Carried by the partitions 19—19 is a metallic electrical conducting member 23, which has the forked portions 24—24 disposed within the recesses 17—17. Mounted within the slots 22—22 are the sockets 25—25, which sockets are 40 screw-threaded for the reception of the ordinary plug forming part of an electric bulb or other translating devices. Said sockets have shoulder portions 26—26 adapted to have sliding relationship with the arcuate walls 18—18 and with the forked portions 24—24 of the electrical conducting member 23. The electric wire 2 is electrically connected to the electrical conducting member 23. It will be apparent without further description that one side of the outside electrical circuit is connected at all times to the sockets 25—25 by way of the electrical conducting member 23. Each of said sockets 25—25 is open at both ends, whereby an electric light may be screwed up into each of said sockets to a position in which the center contact of said electric light bulb will be forced into engagement with the corresponding pin 16. The two sections 6 and 7 may be held together by means of screw bolts 28—28. If desired, an ornamental knob 29 may be clamped between said sections 6 and 7. Inasmuch as the pins 16—16 are connected to terminals of the switching mechanisms 10—10 and the other terminals of said

switching mechanisms 10—10 are connected by way of the contact springs 13—13 to the wire 3, it will be clear that each of said switching mechanisms 10—10 controls the electric circuit through its corresponding 70 electric light bulb 27.

It will be clear that the sockets 25—25 are capable of a rocking movement within the recesses 17—17. The shoulders 26 of the sockets 25—25 have rubbing engagement 75 with the electrical conducting member 23, whereby a good electrical connection between each of said sockets and the electrical conducting member 23 is had regardless of the positions of sockets 25. When a bulb 27 is screwed home in one of the sockets 25, the center contact of said bulb will abut with some force against the corresponding pin 16, a spring action being had due to the action and reaction between the internal screw- 80 threads of each socket 25 and the corresponding pin 16. Due to the pressure exerted, each socket is frictionally held in place. Angular adjustment of each socket is possible, however, through the exertion of a 85 slight amount of force.

The present invention provides a construction which may be manufactured at small cost, which may be readily assembled and which affords a ready means for holding an electric lamp bulb frictionally in adjusted position. Though a preferred embodiment of the present invention has been described in detail, it will be clear that many modifications will occur to those skilled in the art. It is intended to cover all such modifications that fall within the scope of the appended claims.

What is claimed is:

1. A cluster comprising a housing having a plurality of recesses, each having an arcuate wall, electrical conducting members mounted at the axes of each of said arcuate walls, and socket members mounted in each of said recesses and capable of movement 105 about said axes.

2. A cluster comprising a housing having recesses provided with arcuate walls, said housing being provided with slots providing communication between said recesses and the exterior of said housing, electrical conducting means arranged along said walls, and socket members having electrical contact with said conducting means, said socket members being capable of movement in said 115 slots.

3. A cluster comprising a housing having recesses provided with arcuate walls, said housing being provided with slots providing communication between said recesses and the exterior of said housing, electrical conducting means arranged along said walls, socket members having electrical contact with said conducting means, said socket members being capable of movement in said 125 130

- slots, and electrical conducting means mounted in the axes of said arcuate walls and adapted to be engaged by the center contacts of electric plugs located in said sockets.
4. A cluster comprising a two-part housing providing recesses each having an arcuate wall, movably mounted socket members having portions mounted within said recesses, electrical conducting means in said recesses and having contacting relationship with said sockets throughout the range of movement of said sockets, and abutment means of electrical conducting material mounted in the axes of said arcuate walls.
5. A cluster including a two-part housing, switching means mounted in each part of said two-part housing, said switching means having terminals in common, means for connecting said terminal to one side of an electrical circuit, said housing being provided with a plurality of recesses, each having an arcuate wall, electrical conducting means mounted in each of said recesses and having electrical connection with the other side of said electrical circuit, movable sockets having portions mounted in said recesses and having wiping engagement with said electrical conducting means, and electrical contact means connected with the other terminals of said switching mechanisms positioned in the axes of said arcuate walls.
6. A cluster comprising a housing having two cooperating parts of insulating material, said parts being of the same conformation and adapted to be connected together to form an enclosure, a pair of switching mechanisms carried by said housing, said enclosure having a plurality of recesses, each having an arcuate wall, electrical conducting means arranged along said arcuate walls, socket members of conducting material having portions mounted within said enclosures, said sockets being movable and having rubbing engagement with said electrical conducting means, and contact means connected to terminals of said switching mechanisms positioned in the axes of said arcuate walls.
7. A cluster comprising a housing having a plurality of arcuate walls, a plurality of sockets each capable of a movement of translation in said housing, electrical conducting means arranged along said arcuate walls, said sockets having portions in engagement with said conducting means throughout the range of movement of said sockets, and electrical contact means positioned along the axes of said arcuate walls and adapted to form abutment means for the center contacts of electric bulbs mounted in said sockets.
8. A cluster having a plurality of arcuate walls, a plurality of sockets each having portions slideable along said walls, electrical conducting means arranged along said walls for engagement by said sockets, and other electrical contact means positioned along the axes of movement of said sockets and adapted to form abutments for electric bulbs located in said sockets.
9. A cluster including electrical contact means having arcuate surfaces, a plurality of sockets each capable of a movement of translation and having portions adapted to engage said arcuate surfaces, and electrical contact members arranged along the axes of said surfaces and adapted to form abutments for electric light bulbs mounted in said sockets.
10. A cluster including electrical contact means having arcuate surfaces, a plurality of sockets each capable of a movement of translation and having portions adapted to engage said arcuate surfaces, and electrical contact members arranged along the axes of said surfaces and adapted to form abutments for electric light bulbs mounted in said sockets, each of said sockets having a switching mechanism connected in circuit therewith.
11. A lamp holding device including electrical contact means having an arcuate surface, a socket capable of a movement of translation and having a portion adapted to engage said arcuate surface, and an electrical contact member arranged along the axis of said arcuate surface.
12. A holding device for electric lights including a housing, an electrical contact member, a socket carried by said housing, said housing permitting a movement of translation of said socket about said electrical contact as an axis, and an electrical conducting member having rubbing engagement with a portion of said socket throughout the range of movement of said socket.

Signed at Chicago, Illinois, this 29th day of May, 1925.
